UNITED STATES PATENT OFFICE

ARCHIBALD G. SHAVER, OF CHICAGO, ILLINOIS, ASSIGNOR TO THE REGAN SAFETY DEVICES COMPANY, INC., OF NEW YORK, N. Y., A CORPORATION OF NEW YORK

INTERMITTENT INDUCTION-TYPE TRAIN CONTROL

Application filed November 15, 1921, Serial No. 515,242. Renewed April 24, 1929.

This invention relates to a train control system, and more particularly to a train control system of the induction type, and has special reference to the provision of an induction system arranged to be connected to and influenced by a block signalling system, with the induction system responsive to "safety", "caution" and "danger" track conditions to produce corresponding "clear", "caution" and "stop" effects on the train.

A principal object of the present invention comprehends the provision of an induction train control system in which train carried mechanism is operated to produce a plurality of effects such as proceed, speed restrictive and stop effects responsive to the cooperation between train and track magnetic elements or inductoriums with the train carried mechanism giving a tripping or deenergizing operation in each section or block so as to condition the same for further operation and so as to determine the operability thereof to keep the same in proper working order at all times.

A further principal object of the invention relates to the provision of an induction train control system of the type referred to in which the train and track magnetic elements or inductoriums are operated by train carried energy.

Still further objects of the invention are the provision of an inductive train control system of the nature referred to in which an alternating current or like source of energy is employed, the present invention relating particularly to an induction train control system of the type disclosed and claimed in my copending applications Serial No. 422,598 of Nov. 8, 1920 and Serial No. 506,595 of October 10, 1921; and the provision of an intermittent induction type of train control system in which an alternating current generator or like source of energy is carried upon the train and is connected to influence inductively coupled coils in the nature of a transformer, the coils comprising a three-element transformer having two primary coils and one secondary coil, the magnetic flux to the secondary coil of which is shunted by movement of the

coils over a roadside magnetic element to produce or initiate in each track section or block a "tripping" or test operation of the train control mechanism, cooperating inductoriums responsive to track conditions being provided for determining the further state of operation of the train control mechanism after such initiating operation and for resetting the same under a "proceed" track condition; and the still further provision of an induction train control system in which the vehicle or cab apparatus will be controlled whether the engine is moving stack or tender first and with traffic in both directions or in one direction without altering the vehicle carried apparatus or providing pole changers as in usual practice.

To the accomplishment of the foregoing and such other objects as may hereinafter appear, my invention consists in the elements and their relation one to the other, as herein-after particularly described and sought to be defined in the claims, reference being had to the accompanying drawing which shows a preferred embodiment of my invention, and in which:—

Fig. 1 is a diagrammatic view of the vehicle or cab carried apparatus,

Fig. 2 is a diagrammatic view of the track apparatus showing in dotted lines the position of the vehicle and the inductoriums carried thereby,

Fig. 3 is a cross-sectional view through the rails showing the relative positions of the track and the vehicle carried inductoriums,

Figs. 4 and 5 are diagrammatic views of track apparatus showing modifications, and

Fig. 6 is a diagrammatic view of track apparatus designed for traffic in both directions.

Referring now more in detail to the drawings, and more particularly to Figs. 1 to 3 thereof, there is provided as disclosed in my copending application Serial No. 506,595 above referred to, a train control mechanism which comprises the electromagnet M active for controlling the operation of a com-

55

60

70

75

80

85

90

95

100

bined reservoir and brake valve the detailed construction of which is set forth in my Patent No. 1,411,526 of April 4, 1922. The electromagnet M is controlled by a two-element relay B having the elements 19 and 19'. When the current in the said elements are in phase, as under "clear" track conditions, the contacts 22, 31 and 40 controlled by the relay are caused to assume the full line position shown in Fig. 1; and when the currents are out of phase, as for example 180° out of phase, this existing under "caution" track conditions, the said contacts are caused to assume the inclined dotted line position; and when either element of the relay is de-energized, as under "danger" track conditions, the contacts are caused to drop and assume a neutral vertical dotted line position shown in Fig. 1.

With this operation of the relay B under "clear" roadside conditions, the electromagnet M is energized to produce a train proceed effect in the valve controlled thereby, the electromagnet M being normally energized from a train carried alternating current source of energy by the circuit comprising the generator G, conductors 1, 2, 26, coil of magnet M, conductor 41, contact 40 in full line position, conductor 42, and conductors 30, 43, 44, and 10 to the generator G.

Under "caution" roadside conditions the train controlling mechanism M is placed in circuit with a speed circuit controller S so as to produce a vehicle speed restrictive effect, the electromagnet M being energized when the train is proceeding below and being deenergized when the train is proceeding above a predetermined or permissive speed, the said circuit comprising the generator G, conductors 1, 2 and 26, coil of magnet M, conductor 41, contact 40 closed in inclined dotted line position, conductor 45, contact 46 of the speed circuit controller closed when the train is running below a predetermined speed and opened when the train exceeds such predetermined speed, and conductors 47, 44 and 10 to generator G.

Under "danger" track conditions with the contact 40 in the neutral vertical position the circuit to the electromagnet M is opened, the electromagnet deenergized and the valve controlled thereby operated to set the brakes of the train and to disconnect the engineer's brake valve from the main reservoir as disclosed in my Patent No. 1,411,526 above mentioned.

For normally maintaining the relay contact 40 in either of its full or dotted line positions to maintain unlimited speed or restrictive speed effects on the train, I provide a stick circuit including one element of the relay B and controlled by another two element relay A having the elements 5 and 5'. For normal or unlimited speed conditions, the

stick circuit comprises generator G, conductors 1, 2 and 48, contact 25 controlled by the element 5 of relay A, resistance 24, conductor 23, contact 22 in full line position, conductors 49 and 50, relay element 19, conductors 51, 52 and 53, contact 31 closed in full line position, conductor 54, resistance 55, contact 56 closed under the control of the relay element 5, and conductor 57 to generator G. The element 19' of the relay B is energized through the circuit including the generator G, conductors 10 and 9, coil of element 19', and conductor 8. Under these normal conditions the currents in the elements 19 and 19' of relay B are in phase and the contacts 22, 31 and 40 are operated by the relay to maintain the full line position.

When the currents in the elements 19—19' are out of phase, this being a condition produced by means to be described hereinafter, the contacts 22, 31 and 40 are moved to the right-hand dotted line position and are retained in this position by the train stick circuit as follows: from generator G, conductors 1, 2 and 48, contact 25 closed, resistance 24, conductor 23, contact 22 in inclined dotted line position, conductors 52 and 51, relay element 19, conductors 50, 49, 53 and 59, contact 31 in inclined dotted line position, conductor 54, resistance 55, contact 56 closed, and conductor 57 to generator G. With this circuit it will be noted that the currents in elements 19 and 19' are 180° out of phase, and the stick circuit will therefore maintain the contacts 22, 31 and 40 in their dotted line positions.

Under "danger" track conditions the stick circuit is broken by the opening of the contacts 25 and 56 controlled by the relay A as to be described presently, and the contacts 22, 31 and 40 assume the vertical dotted line positions with the result that the electromagnet M is deenergized.

For controlling the positioning of the contacts of the relay B so as to impress upon the train controlling means M a desired effect, I provide cooperating vehicle and roadside magnetic means or elements, and more specifically vehicle and roadside inductoriums, the roadside inductoriums being preferably under the control of a block signalling system and being influenced by the same to respond to "clear", "caution" and "danger" track conditions and to indicate such conditions, and the vehicle inductoriums being arranged for movement over the roadside inductoriums and to cooperate with the latter to receive and transmit the indications of the same to the train circuits and to the relay B to correspondingly influence and operate the same. To these ends I provide a train transmitting inductorium 28 connected to the vehicle source of energy G by means of the conductors 1, 2, 48 and 26, the condenser 27, and conductors 29, 30, 48, 44 and 10, and

5 a train receiving inductorium 16 connected to operate and control a normally deenergized two element relay C having the elements 13 and 13', the element 13 being connected to the inductorium 16 by means of the conductors 14 and 15, and the element 13' of the relay being connected to the generator G by means of the conductors 10, 12 and 11.

10 For cooperation with the train transmitting and receiving inductoriums, I provide roadside receiving and transmitting inductoriums here shown arranged in pairs T'-T' and T-T, the said roadside inductoriums being electrically connected by means 15 operative to reverse and to break the circuit connections therebetween, the said means comprising the make and break contacts 34 under the control of a home relay H, and the pole changing contacts 33 under the control of distant relay D, energization of the home and distant relays H and D taking place under "clear" track conditions, resulting in the 20 positioning of the contacts as shown in Fig. 1 to connect the inductoriums T'-T' to the inductoriums T-T by means of the circuit including the conductors 35 and 32. When under "caution" track conditions the relay D is deenergized, the contacts 33 are released to reverse the circuit connections between the 25 inductorium coils in a manner as will be apparent from a consideration of Fig. 2. When under "danger" track conditions the home relay H is deenergized, the contacts 34 are actuated to break the connections between 30 the inductorium coils.

35 With this construction it will be seen that in the movement of the train and in the passage of the train inductoriums over the track inductoriums, an impulse will be transmitted 40 from the train transmitting inductorium 28 to the track receiving inductoriums T'-T', and that such impulse may be transmitted in a given phase, modified to a reverse or opposite phase, or inhibited for influencing the 45 track inductoriums T-T for in turn influencing the train receiving inductorium 16 to energize the element 13 of the relay C with current in a given phase or in an opposite phase under "clear" and "caution" conditions, 50 respectively, with no energization taking place under "danger" conditions, the transmission, modification or inhibiting of the impulse received by the roadside inductoriums T'-T' being controlled by the circuit 55 make and break and pole changing devices which in turn are influenced by the home and distant relays H and D of the block signalling system. It will be noted that the cooperation between the train and track inductoriums is momentary only as the former moves over the latter in the movement of the vehicle, a set of train inductoriums being provided for each section or block of the track. The track inductoriums, it will be 60 observed, constitute a roadside reflector with

means for controlling the phase angle thereof, the said roadside reflector receiving energy from the vehicle carried or train inductorium and reflecting or retransmitting the energy to the vehicle under favorable, such as clear or caution, roadside conditions. 70

75 The roadside inductoriums T-T and T'-T' are arranged in pairs as above referred to, a multiple roadside inductorium system being here provided, each inductorium being divided into a plurality of inductoria arranged in tandem. It has been found by experimentation that where an inductorium is thus divided into a plurality of sections, that under similar operating conditions, as for example with the same amount of energy used, a multiple inductoria system produces impulses of greater amplitude, this being especially desirable for high speed trains. More specifically where a single inductorium is used the impulse with a given amount of energy employed may be represented by a long flat curve, and where such inductorium is divided into two sections, the sum of the length of the sections being substantially equal to the length of the single section, the successive impulses produced will each be of greater amplitude, this being a desirable characteristic in the operation of a relay, and at high speeds the succession of 80 waves produced will tend to merge together to produce an impulse having an effective greater length than the impulse produced with a single inductorium. 90

95 Controlled by the relay C there are provided contact armatures 17 and 18 which under normal conditions assume the vertical dotted line positions shown in the figure due to the normal deenergization of the relay C, the said contacts being moved to the full line position shown when the element 13 of the relay is energized with current in phase with the energizing current of the element 13', and being moved to assume the inclined dotted line position shown in the figure when the element 13 is energized with current of an opposite phase. 100

105 When under "clear" track conditions the contacts 17 and 18 are made to momentarily assume their full line position, the element 19 of the relay B is energized by the closing of the circuit comprising generator G, conductors 10, 44 and 60, contact 18 in full line position, conductors 61, 52 and 51, relay element 19, conductors 50, 49, 58 and 21, contact 17 in full line position, and conductor 20 to generator G, the energization of element 19 by this circuit causing the contacts 22, 31 and 40 thereof to assume the full line position to 110 close the stick circuit and the circuit of the electromagnet M, producing "clear" or "proceed" conditions on the train. 115

120 When under "caution" track conditions the contacts 17 and 18 are momentarily caused to 125

- assume the inclined dotted line position, the relay element 19 is energized by current of a phase opposite to that in the element 19' by means of the circuit comprising the generator G, conductors 10, 44 and 60, contact 18 in inclined-dotted line position, conductors 21, 58, 49 and 50, relay element 19, conductors 51, 52, 61 and 62, contact 17 closed in inclined dotted line position, and conductor 10 to generator G. With the closing of this circuit the element 19 is energized by current of a phase opposite to that in element 19', and the contacts 22, 31 and 40 are moved to the inclined dotted line position to close the corresponding stick circuit and the circuit including the electromagnet M and the speed controller S, producing "caution" or speed restrictive conditions on the train.

When under "danger" track conditions the element 13 of relay C is not energized, the controlling or operating circuit for the element 19 of relay B is not closed, and should the contacts 22, 31 and 40 be in a vertical dotted line position, the said contacts will remain in such position for producing a "stop" effect on the train.

For the purpose of conditioning the vehicle carried mechanism for operation and control by the train and track inductoriums so that the train circuits are made to respond to the indications of the track inductoriums, and for the further purpose of automatically giving the train control apparatus a tripping and test operation in each section or block in order to automatically check the operability of the same at all times, there are provided cooperating train and track magnetic means for periodically tripping or deenergizing the element 5 of relay A, and more specifically for opening the stick circuit controlled thereby at the contacts 25 and 56. To these ends the relay A heretofore mentioned is provided, the element 5' thereof being always energized from the generator G, the said element being connected to the generator by means of the conductors 1 and 63, the element 5 being connected to, to be energized by a coil D' by means of the conductors 6 and 7, the said coil D' being inductively coupled to the spaced coils J and J' which in turn are connected to be energized by the generator G by means of the conductors 2, 3 and 4. The inductively coupled coils D', J and J' comprise or constitute a three element transformer, the coils J and J' constituting the primary coils of the transformer and the coil D' constituting the secondary coil of the transformer. These coils are arranged preferably in parallel relation, the outer coils J and J' functioning to normally induce current in the central coil D' for normally energizing the relay element 5. Cooperating with the transformer J—J'—D' there is provided for each section or block an inert track element E, the trans-

former J—J'—D' being adapted to cover the track element E in the passage of the vehicle thereover. With this construction it will be seen that normally when the train is running between track elements the magnetic flux transmitted from the cores of the primary coils to the core of the secondary coil of the transformer induces a current in the coil D' sufficient to energize the relay element 5 to normally keep the armatures 25 and 56 closed. The primary of the transformer comprises, therefore, an energy transmitting coil set having a plurality of coils and the secondary of the transformer comprises an energy receiving coil set, the coil sets interlinking in two magnetic loop paths. When the transformer covers the track element, the magnetic flux passes from the cores of the coils J—J' down to and through the track element E, the passing of the flux through the inert track element E resulting in a diverting or shunting of the magnetic flux from the core of the coil D'. The coil D' is thus magnetically shunted, causing an effective deenergization of the relay element 5, with the result that the armatures 25 and 56 are opened, opening the stick circuit of the relay B. The shunting of the flux of the secondary coil is therefore a changing in the energy transference between the inductively coupled coils which effectively deenergizes the relay element 5 and the train carried mechanism. This shunting action is momentary only, and after the transformer passes the inert track element the magnetic flux through the core of the coil D' is reestablished, reenergizing the relay element 5 for closing the contacts 25 and 26. With this construction it will therefore be seen that in each section or block of the track the stick circuit of the relay B is opened and the contacts controlled thereby moved to vertical opened position, conditioning the relay for response to the operation of the train and track inductoriums heretofore described, the train and track inductoriums being brought into cooperative relation immediately after the shunting operation with reference to the coil D' takes place, as will clearly appear from a consideration of Fig. 2 of the drawings, the time interval between the shunting action and the operation of the inductoriums being insufficient to permit the brakes of the train to be set.

Experiments seem to indicate that the theory of operation or action of the transformer combination J—J'—D' and of the inductive influence of the inert inductor E to produce the magnetic shunting of the secondary of the transformer or the shunting or diverting of the lines of flux may be taken substantially as follows, it being understood, however, that this theory of operation is given by way of explanation only, and not by way of limitation of the invention:

If we let M =Total M. M. F., the magnetomotive force in the magnetic circuits of the transformer $J-J'-D'$

Let ϕ =Total flux

5 R_j =Reluctance of the primary
 R_r =Reluctance of the remainder
of the magnetic circuit

Then

$$10 M = \phi(R_j + R_r) \quad (1)$$

Transposing,
 $M - \phi R_j = \phi R_r \quad (2)$

Equation (1) shows that the total magnetomotive force is made up of the magnetomotive force active on the primary and the magnetomotive force active on the remainder of the magnetic circuit. In Equation (2) the quantity ϕR_r may be considered the magnetic potential difference which is effective 15 on the remainder of the magnetic circuit for energizing purposes and more particularly for energizing the secondary D' .

When the vehicle carried transformer $J-J'-D'$ moves over the track element E , two effects are produced, substantially as follows:

(a) When the vehicle carried transformer inductor moves over the track element the flux ϕ increases and since R_j is constant, the product ϕR_j increases, and from Equation 20 (2) it will be seen (assuming M to remain constant) that the effective magnetic potential difference ϕR_r operative for energizing purposes decreases so that the energizing current for the relay A is effectively decreased.

(b) The magnetomotive force M , however, does not remain constant. When the vehicle carried transformer moves over the track element, the reactive effect on the vehicle carried inductor due to the decrease in reluctance in the magnetic circuit produces a decrease in the magnetomotive force M since the inductance of the energizing primary coil is increased with a corresponding decrease in energizing current. The magnetomotive force (ampere turns) therefore is decreased and thus the difference between this and ϕR_j is decreased still further, the resulting magnetic potential difference active for 35 energizing the secondary being thereby still further reduced. Experiments appear to determine that the decrease in the magnetic potential difference due to the first effect (a) is the more predominant of the two, the resultant change being due substantially to this factor, the magnetic flux through the secondary being therefore actually shunted or diverted, although part of the total magnetic flux is somewhat decreased due to the 50 second mentioned factor (b).

Referring now to the arrangement shown in Fig. 4 of the drawings, the roadside inductoriums $T-T'$ and T^2-T^2 are modified so as to be positioned exteriorly of the track rails 55 as $R-R$, the vehicle carried apparatus being

correspondingly modified to position the inductoriums 16 and 28 so as to be movable directly over the roadside inductoriums.

In the arrangement shown in Fig. 5 of the drawings the disposition of the track inductoriums is modified, the said track inductoriums being all arranged in tandem, the inductoriums on the vehicle being correspondingly modified to cooperate with this arrangement.

In the construction shown in Fig. 6 two sets of roadside inductoriums are provided for each inert element E , one set of inductoriums being disposed on one side of the element, and the other set upon the other side of the said element E , so that the vehicle carried elements will be actuated if moved in either direction along the track. If the vehicle moves with respect to the element E from left to right, for example, the train mechanism will first be affected by the element E and then by the set of inductoriums to the right of the said element; while with the vehicle moving in the reverse direction, as from right to left, the vehicle carried mechanism will first be influenced by the inert element and then by the track inductoriums to the left thereof, this system being adaptable, therefore, to traffic in one or both directions without modifying or changing the vehicle carried apparatus.

The operation of my improved induction train control system will in the main be apparent from the above detailed description thereof. It will be seen that in each section or block the inert magnetic shunting member E of the track mechanism will momentarily magnetically shunt the coil D' of the three element transformer $J-J'-D'$, causing an opening of the stick circuit of the relay element 19, releasing the armature contacts 22, 31 and 40 thereof. Immediately after this shunting action the train and track inductoriums 16, 28, $T-T$ and T^2-T^2 are brought into cooperation to determine the further state of operation of the relay B , these inductoriums functioning as pick-up or resetting mechanism. Under "clear" track conditions an impulse is transmitted to the train inductorium 16 to momentarily operate the reset element 13 of the relay C to actuate the contacts 17 and 18 to full line position, this in turn closing a circuit to the relay element 19 to energize the same with "in phase" current, such energization resulting in the contacts 22, 31 and 40 assuming their full line positions for closing the stick circuit and the circuit of the electro-magnet M , the said stick circuit being thereafter maintained closed by the reenergization of the relay element 5 due to the passage of the transformer beyond the track element E . Under "caution" track conditions an impulse of a phase opposite to that produced under "clear" track conditions will be transmitted to the

train inductorium 16 for momentarily energizing the element 13 of the relay C with out of phase current, this momentarily closing an energizing circuit to the relay element 19 of relay B with an out of phase current for moving the contacts controlled thereby to their dotted line positions, placing the train under speed restrictive operation. Under "danger" track conditions no impulse is transmitted to the train inductorium, with the result that the element 13 of relay C remains deenergized and the relay element 19 of relay B is unenergized and the contacts controlled by the latter remain in neutral circuit opening position for bringing the train to a halt.

After the train has been brought to a halt the same may be again set in motion by the operation of a release key K operated by the engineer so as to cause the members 65 and 66 to connect the relay element 19 to the generator G by means of the circuit including the generator, conductors 10 and 67, contact 66, conductor 50, relay element 19, conductor 51, conductor 68, contact 65 to generator G, this connection causing the energization of element 19 of relay B with an out of phase current so that the armatures of relay B will be moved to the inclined dotted line position, this placing the speed circuit controller in circuit with the electromagnet M so that the train can proceed under or at a predetermined speed only.

While I have shown my device in the preferred form, it will be apparent that many changes and modifications may be made in the structure disclosed, without departing from the spirit of the invention, defined in the following claims.

I claim:

1. In combination, vehicle carried mechanism, means for operating the said mechanism for producing a given condition comprising a plurality of vehicle energy transmitting coils, a vehicle energy receiving coil inductively coupled thereto, and a roadside device for magnetically shunting said receiving coil in the movement of the vehicle, and means for operating the vehicle carried mechanism for producing a different condition therein.

2. In combination, vehicle carried mechanism, means for operating the said mechanism for producing a given condition comprising a plurality of vehicle energy transmitting coils, a vehicle energy receiving coil inductively coupled thereto, and a roadside device for magnetically shunting said receiving coil in the movement of the vehicle, and cooperative vehicle and roadside means for operating the vehicle carried mechanism for producing a different condition therein.

3. In combination, vehicle carried mechanism, means for periodically operating said mechanism for producing a given condition comprising a plurality of vehicle energy

transmitting coils, a vehicle energy receiving coil inductively coupled thereto, and a roadside device for magnetically shunting said receiving coil in the movement of the vehicle, and means for periodically operating the vehicle carried mechanism for modifying said condition.

4. In combination, vehicle carried mechanism, means for operating the said mechanism for producing a given condition comprising a plurality of vehicle energy transmitting coils, a vehicle energy receiving coil inductively coupled thereto, and a roadside device for magnetically shunting said receiving coil in the movement of the vehicle, and cooperative vehicle and roadside inductoriums for operating the vehicle carried mechanism for producing a different condition therein.

5. In combination, vehicle carried mechanism including a normally closed operating circuit, means for opening the circuit in the movement of the vehicle comprising a plurality of vehicle energy transmitting coils, a vehicle energy receiving coil inductively coupled thereto and roadside mechanism comprising a roadside element for magnetically shunting said receiving coil, and means for determining the further operation of said circuit.

6. In combination, vehicle carried mechanism including a normally closed operating circuit, means for opening the circuit in the movement of the vehicle comprising a plurality of vehicle energy transmitting coils, a vehicle energy receiving coil inductively coupled thereto, and roadside mechanism comprising a roadside element for magnetically shunting said receiving coil, and cooperative vehicle and roadside inductoriums for determining the further operation of said circuit.

7. In combination, vehicle carried mechanism including a train control means and a speed controller, means for influencing the train control means in the movement of the vehicle for producing a given condition therein comprising a plurality of vehicle energy transmitting coils, a vehicle energy receiving coil inductively coupled thereto and a roadside device for magnetically shunting said receiving coil, instrumentalities for influencing the train control means for producing another condition therein, and provisions for placing the train control means under the influence of the speed controller under a predetermined operation of said instrumentalities.

8. In a train control system, vehicle carried mechanism, means for influencing the said mechanism in the movement of a vehicle over a roadway comprising a plurality of vehicle energy transmitting coils, a vehicle energy receiving coil inductively coupled thereto, and a roadside device for magnet-

ically shunting said receiving coil, and means for determining the operation of said mechanism so influenced including cooperative vehicle and roadside magnetic elements.

5 9. In a train control system, vehicle carried mechanism, means for periodically influencing the said mechanism in the movement of a vehicle over a roadway comprising a plurality of vehicle energy transmitting 70 coils, a vehicle energy receiving coil inductively coupled thereto and a roadside device for magnetically shunting said receiving coil, and means for periodically determining the operation of said mechanism so influenced 75 including cooperative vehicle and roadside magnetic elements.

10 10. In an inductive train control system, vehicle carried mechanism, means for influencing the same in the movement of the vehicle to produce a "danger" effect therein comprising a plurality of vehicle energy transmitting coils, a vehicle energy receiving coil inductively coupled thereto, and a roadside device for magnetically shunting 80 said receiving coil, and means operable substantially when the same is so influenced for differently modifying the effect under "safe" and "caution" track conditions to produce proceed and speed restrictive effects therein.

15 11. In an inductive train control system, vehicle carried mechanism, means for influencing the same in the movement of the vehicle to produce a "danger" effect therein comprising a plurality of vehicle energy transmitting coils, a vehicle energy receiving coil inductively coupled thereto, and a roadside device for magnetically shunting said receiving coil, and vehicle and roadside inductorium means operable substantially 85 90 when the same is so influenced for differently modifying the effect under "safe" and "caution" track conditions to produce proceed and speed restrictive effects therein.

20 12. In combination, vehicle carried mechanism, means for operating the said mechanism, for producing a given condition comprising a source of energy, a controlling relay, three parallelly arranged coils including two outer coils and an inner coil inductively coupled thereto, the outer coils being connected to the source of energy and the inner coil to the controlling relay and a roadside device for magnetically shunting said inner coil in the movement of the vehicle, 95 and means for operating the vehicle carried mechanism for producing a different condition therein.

25 13. In combination, vehicle carried mechanism, inductive means for operating the vehicle carried mechanism for producing a given condition therein, and means for operating the said mechanism for producing a different condition therein comprising co-operating vehicle and roadside inductoriums, 100 the said roadside inductoriums including a

plurality of inductorium elements arranged longitudinally in tandem.

14. In combination, vehicle carried mechanism, inductive means including roadside mechanism for influencing the vehicle carried mechanism in the movement of the vehicle over a roadway for producing a given condition, and means for determining the operation of said vehicle carried mechanism so influenced for producing a different condition 75 including a vehicle energy receiving means and a roadside energy transmitting means, the said roadside energy transmitting means comprising a plurality of connected inductoriums arranged longitudinally in tandem. 80

15. In combination, vehicle carried mechanism, means including roadside mechanism for influencing the vehicle carried mechanism in the movement of the vehicle over a roadway for producing a given condition, 85 and means for influencing the vehicle carried mechanism for producing a different condition including vehicle energy transmitting and receiving inductoriums and track energy receiving and transmitting inductoriums, 90 each of the said track inductoriums comprising a plurality of inductorium elements arranged in tandem.

16. In combination, roadside apparatus for impressing roadside conditions on moving vehicles comprising a plurality of roadside energy receivers arranged in tandem, a plurality of roadside energy transmitters arranged in tandem, and means for selectively connecting the said receivers to the said 100 transmitters.

17. In combination, roadside apparatus for impressing roadside conditions on moving vehicles comprising a plurality of roadside energy receivers arranged in tandem, a plurality of roadside energy transmitters arranged in tandem, means for selectively connecting the said receivers to the said transmitters, and provisions for disconnecting the receivers from the said transmitters. 110

18. In combination, vehicle carried mechanism, means for operating the said mechanism for producing a given condition comprising a three element transformer having a primary and secondary, and a roadside device for magnetically shunting the secondary in the movement of the vehicle, and means for operating the vehicle carried mechanism for producing a different condition therein. 115

19. In combination, vehicle carried mechanism, means for operating the said mechanism for producing a given condition comprising a three element transformer including a primary and a secondary and a roadside device for magnetically shunting the secondary in the movement of the vehicle, and co-operative vehicle and roadside means for operating the vehicle carried mechanism for producing a different condition therein. 120

20. In combination, vehicle carried mecha-

- nism, means for operating the said mechanism for producing a given condition comprising a three element transformer including a primary and a secondary and a roadside element for inductively shunting the said secondary in the movement of the vehicle, and cooperative vehicle and roadside inductors for operating the vehicle carried mechanism for producing a different condition therein.
21. In combination, vehicle carried mechanism including a normally closed operating circuit, means for opening the circuit in the movement of the vehicle comprising a three element transformer including a primary and a secondary and roadside mechanism including a roadside element for magnetically shunting the secondary, and cooperative vehicle and roadside inductors for determining the further operation of said circuit.
22. In a train control system, vehicle carried mechanism, means for periodically influencing the said mechanism in the movement of the vehicle over a roadway comprising a three element transformer including a primary and a secondary and a roadside device for inductively shunting the secondary, and means for periodically determining the operation of said mechanism so influenced including cooperative vehicle and roadside magnetic elements.
23. An intermittent inductive train control system comprising, in combination, vehicle carried mechanism including inductively coupled coils normally coupled together for direct energy transference therebetween, said coupled coils comprising an energy transmitting coil set and an energy receiving coil set, one of said sets having a plurality of coils, and roadside mechanism including an inductor cooperating inductively with the vehicle carried coupled coils when said coils move over and in proximity to said roadside inductor in the movement of the vehicle over the roadside for decreasing the direct energy transference between said coupled coils to produce a given condition in said vehicle carried mechanism, and means for operating the vehicle carried mechanism for producing a different condition therein.
24. An inductive train control system comprising, in combination, vehicle carried mechanism including inductively coupled coils normally coupled together for energy transference therebetween, said coupled coils comprising an energy transmitting coil set and an energy receiving coil set, one of said sets having a plurality of coils, a train control device normally energized by said coils, and roadside mechanism for effecting the deenergization and restoration of said train control device comprising an inductor cooperating inductively with the vehicle carried coupled coils when said coils move over and in proximity to said inductor in the movement of the vehicle over the roadside for decreasing the effective energy transference between said inductively coupled elements to deenergize said device, and inductive means controlled from the roadside for restoring the operation of said train control device.
25. An intermittent inductive train control system comprising, in combination, vehicle carried mechanism including inductively coupled coils normally coupled together for direct energy transference therebetween and having reluctance in the inductive path therebetween, said coupled coils comprising an energy transmitting coil set and an energy receiving coil set, one of said sets having a plurality of coils, the said coils interlinking in two closed magnetic loops, roadside mechanism including spaced inductors cooperating intermittently with the vehicle carried mechanism in the movement of the vehicle over the roadside, a roadside inductor cooperating inductively with the vehicle carried inductively coupled coils when said coils move over and in proximity to said roadside inductor for decreasing the direct energy transference between said inductively coupled coils to produce a given condition in said vehicle carried mechanism, and means for operating the vehicle carried mechanism for producing a different condition therein.
26. An inductive train control system comprising, in combination, vehicle carried mechanism including a source of energy, a train controlling device, an energy transmitting coil set connected to said source of energy, an energy receiving coil set normally inductively coupled to said energy transmitting coil for receiving energy therefrom and connected to said train controlling device for normally energizing the same, one of said coil sets comprising a plurality of coils spaced from the other coil set to provide two loop magnetic paths, the said coils being coupled with reluctance in the inductive path therebetween, roadside mechanism including an inductor cooperating inductively with the vehicle carried energy transmitting and receiving coils when said coils move over and in proximity to said inductor for affecting the direct energy transference between said vehicle inductively coupled coils to effectively deenergize and trip said train controlling device and said vehicle carried mechanism, and means for restoring the operation of said vehicle carried mechanism.
27. An intermittent inductive train control system comprising, in combination, vehicle carried mechanism including an alternating current source of energy, a train controlling device, a pair of energy transmitting coils connected in circuit to said source of energy, an energy receiving coil normally inductively coupled to said energy transmitting coil for receiving energy therefrom and connected directly in circuit to said

- train controlling device for normally energizing said device, roadside mechanism including spaced magnetic members cooperating intermittently with the vehicle carried mechanism in the movement of the vehicle over the roadside, a roadside magnetic member cooperating inductively with the vehicle carried coupled coils when said coils move over said magnetic member for changing the energy transference between said inductively coupled coils to effectively deenergize said train controlling device and said vehicle carried mechanism, and means for restoring the operation of said vehicle carried mechanism.
28. An intermittent inductive train control system comprising, in combination, vehicle carried mechanism including an alternating current source of energy, a train controlling device, an energy transmitting coil set connected in circuit to said source of energy, an energy receiving coil set normally inductively coupled to said energy transmitting coil for receiving energy therefrom and connected directly in circuit to said train controlling device for normally energizing said device, one of said coil sets comprising a plurality of coils, the said coil sets interlinking in two magnetic loops, and roadside mechanism including an inductor cooperating inductively with the vehicle carried coupled coils when said coils move over said inductor for changing the energy transference between said inductively coupled coils to effectively deenergize said train controlling device and trip said vehicle carried mechanism, said vehicle carried and roadside mechanism including vehicle carried and roadside inductors operated from a vehicle carried source of energy and effective for restoring the vehicle carried mechanism.
29. An intermittent inductive train control system comprising, in combination, vehicle carried mechanism including an alternating current source of energy, a train controlling device, an energy transmitting coil set connected in circuit to said source of energy, an energy receiving coil set normally inductively coupled to said energy transmitting coil for receiving energy therefrom and connected directly in circuit to said train controlling device for normally energizing said device, one of said coil sets comprising a plurality of coils, the said coil sets interlinking in two magnetic loops, and roadside mechanism including an inductor cooperating inductively with the vehicle carried coupled coils when said coils move over said inductor for changing the energy transference between said inductively coupled coils to effectively deenergize said train controlling device and trip said vehicle carried mechanism, said vehicle carried and roadside mechanism including a vehicle carried inductor and a roadside inductor operated from said vehicle carried source of energy and effective for restoring the vehicle carried mechanism.
30. An intermittent inductive train control system comprising, in combination, vehicle carried mechanism including a source of energy, a train controlling device, an energy transmitting coil set connected to said source of energy, an energy receiving coil set normally inductively coupled to said energy transmitting coil for receiving energy therefrom and connected to said train controlling device for normally energizing said device, one of said coil sets comprising a plurality of coils, and roadside mechanism including an inductor cooperating inductively with the vehicle carried energy transmitting and receiving coils when said coils move over and in proximity to said inductor for decreasing the direct energy transference between said vehicle inductively coupled coils and thereby tripping said vehicle carried mechanism, said vehicle carried and roadside mechanism including vehicle carried and roadside inductors operative for restoring the vehicle carried mechanism, and a vehicle carried source of energy for operating the said inductors.
31. An intermittent inductive train control system comprising, in combination, vehicle carried mechanism including a source of energy, a train controlling device, an energy transmitting coil set connected to said source of energy, an energy receiving coil set normally inductively coupled to said energy transmitting coil for receiving energy therefrom and connected to said train controlling device for normally energizing said device, one of said coil sets comprising a plurality of coils, the said coil sets interlinking in two magnetic loop paths, and roadside mechanism including an inductor cooperating inductively with the vehicle carried energy transmitting and receiving coils when said coils move over and in proximity to said inductor for decreasing the direct energy transference between said vehicle inductively coupled coils and thereby tripping said vehicle carried mechanism, and means energized wholly from said vehicle carried source of energy and including a circuit on the roadside for restoring said vehicle carried mechanism only if said circuit on the roadside is closed.
32. An intermittent inductive train control system comprising, in combination, vehicle carried mechanism including an alternating current source of energy, a train controlling device, an energy transmitting coil set connected in circuit to said source of energy, an energy receiving coil set normally inductively coupled to said energy transmitting coil for receiving energy therefrom and connected directly in circuit to said train controlling device for normally energizing said device, one of said coil sets comprising a plurality of coils, and roadside mechanism including an inductor cooperating inductively with the vehicle carried energy transmitting and receiving coils when said coils move over and in proximity to said inductor for decreasing the direct energy transference between said vehicle inductively coupled coils and thereby tripping said vehicle carried mechanism, said vehicle carried and roadside mechanism including a vehicle carried inductor and a roadside inductor operated from said vehicle carried source of energy and effective for restoring the vehicle carried mechanism.

hicle carried coupled coils when said coils move over said inductor for changing the energy transference between said inductively coupled coils to effectively deenergize said train controlling device and trip said vehicle carried mechanism, and means energized wholly from said vehicle carried source of energy and including a circuit on the roadside for restoring said vehicle carried mechanism only if said circuit on the roadside is closed.

33. In an inductive train control system, vehicle carried mechanism including an indicating means selectively movable in accordance with roadside conditions into either of two active positions, an operating means therefor for moving the same to either of such positions and a holding means for holding the indicating means in either of such positions, and cooperative vehicle and roadside inductive mechanism for rendering the holding means inoperative so as to trip the indicating means and for actuating the operating means to move the indicating means to either of its selected active positions.

34. In an inductive train control system, vehicle carried mechanism including an indicating means movable into "clear", "caution" and "danger" positions, an operating means therefor for moving the same to the "clear" or "caution" position, and a holding means for holding the indicating means in either the "clear" or "caution" position, and cooperative vehicle and roadside inductive mechanism for rendering the holding means inoperative so as to trip the indicating means to move the same to the "danger" position and for actuating the operating means to move the indicating means to the "clear" or "caution" position depending upon the roadside condition.

35. In an inductive train control system, vehicle carried mechanism including an indicating means having an element selectively movable in accordance with roadside conditions into either of two active positions, an operating means therefor for moving the same to either of such positions and a holding means for holding the indicating means in either of such positions, and cooperative vehicle and roadside inductive mechanism for rendering the holding means inoperative so as to trip the indicating means and for actuating the operating means to move the indicating means to either of its selected active positions.

36. In an inductive train control system, vehicle carried mechanism including a three position indicating means having an element selectively movable into either of two active positions, an operating means therefor for moving the same to either of such positions and a holding means for holding the indicating means in either of its selected positions, and cooperative vehicle and roadside inductive

mechanism for rendering the holding means inoperative so as to trip the indicating means and for momentarily actuating the operating means to move the indicating means to its selected active position, and means whereby the operation of the holding means will be restored after said momentary actuation of the operating means.

37. In an inductive train control system, vehicle carried mechanism including an indicating means having an element movable into "clear" and "caution" indicating positions, an operating means therefor for moving the same to either of said positions and a holding means for holding the indicating means in either of such positions, and cooperative vehicle and roadside inductive mechanism for rendering the holding means inoperative so as to trip the indicating means and for selectively actuating the operating means to move the indicating means to either the "clear" to "caution" position depending upon the roadside condition.

38. In an inductive train control system, vehicle carried mechanism including a three position indicating means movable into "clear", "caution" and "danger" positions, an operating means therefor for moving the same to the "clear" or "caution" position, and a holding means for holding the indicating means in either the "clear" or "caution" position, and cooperative vehicle and roadside inductive mechanism for rendering the holding means inoperative so as to trip the indicating means to move the same to the "danger" position and for actuating the operating means to move the indicating means to the "clear" or "caution" position depending upon the roadside condition.

39. In a train control system, vehicle carried mechanism comprising a three position movable indicating means, an operating magnet therefor, a holding magnet therefor for normally holding the indicating means in position, a vehicle carried inductive circuit controlled from the roadside for normally effecting the energization of the holding magnet and adapted to be influenced for rendering the said holding magnet inoperative, and an independent vehicle carried inductive circuit also controlled from the roadside for determining the actuation of the operating magnet when the holding magnet is rendered inoperative.

40. In a train control system, vehicle carried inductor apparatus having a part supplied with A. C., roadside inductor apparatus inductively associated with the vehicle inductor apparatus, a train control phase relay controlled by the phase angle of a part of said roadside inductor apparatus, and a holding means for the phase relay releasable by coaction of the vehicle and roadside inductor apparatus.

41. Railway signalling means comprising

a normally energized inductor apparatus carried by the vehicle, a roadside inductor apparatus arranged adjacent the track, a condenser connected to said roadside inductor apparatus to predetermine its phase angle, means operated by the proximity of a vehicle on the tracks to disconnect said condenser, and signalling mechanism operated by said vehicle inductor apparatus and controlled by said roadside inductor apparatus, said signaling mechanism being controlled by changes in phase angle determined by the operation of said roadside inductor apparatus.

42. Railway signalling means comprising a normally energized inductor apparatus carried by the vehicle, a roadside inductor apparatus arranged adjacent the track, a condenser connected in circuit with said roadside inductor apparatus to predetermine its phase angle, a relay adapted to disconnect said condenser from said roadside inductor apparatus when said relay is de-energized, means controlled by the proximity of a vehicle on the track for deenergizing said relay, and a signalling mechanism operated by said vehicle inductor apparatus and controlled by said roadside inductor apparatus, said signaling mechanism being controlled by changes in phase angle determined by the operation of said roadside inductor apparatus.

43. Railway signalling means comprising a normally energized vehicle carried inductor apparatus supplied with alternating current from a source carried by the vehicle, a roadside inductor reflector apparatus adapted to receive electro-magnetic-energy from the vehicle and to reflect under certain conditions electro-magnetic-energy to said vehicle carried inductor apparatus, means for controlling the phase angle of said roadside reflector whereby the phase angle of the vehicle inductor apparatus will be affected by said roadside reflector when the vehicle is adjacent to said roadside reflector, and cab signalling mechanism operated by said vehicle inductor apparatus and controlled by the phase angle of said roadside inductor apparatus.

44. In a train control system, normally energized vehicle carried inductor apparatus supplied with A. C., roadside inductor apparatus inductively associated with the vehicle inductor apparatus, a train control phase relay controlled by the phase angle of a part of said roadside inductor apparatus, and a holding means for the phase relay releasable by variation of the magnetic characteristics of the vehicle inductor apparatus.

In testimony whereof I affix my signature.

ARCHIBALD G. SHAVER.
